(57) **CLAIM**

The ornamental design for a sofa, as shown and described.

DESCRIPTION

FIG. 1 is a front, right, top perspective view of a first piece, a second piece, and a third piece in a combined state, showing my new design;

FIG. 2 is a front, right, top perspective view of the first piece and the second piece in a combined state, showing my new design;

FIG. 3 is a front, right, top perspective view of the first piece and the third piece in a combined state, showing my new design;

FIG. 4 is an enlarged view of detail 4 in FIG. 1;

FIG. 5 is an enlarged view of detail 5 in FIG. 1;

FIG. 6 is an enlarged view of detail 6 in FIG. 1;

FIG. 7 is an enlarged view of detail 7 in FIG. 1;

FIG. 8 is an enlarged view of detail 8 in FIG. 2;

FIG. 9 is a front, right, top perspective view of the first piece of the sofa, showing my new design;

FIG. 10 is a rear, left, bottom perspective view thereof;

FIG. 11 is a front elevational view thereof;

FIG. 12 is a rear elevational view thereof;

FIG. 13 is a left side view thereof;

FIG. 14 is a right side view thereof;

FIG. 15 is a top plan view thereof;

FIG. 16 is a bottom plan view thereof;

FIG. 17 is an enlarged view of detail 17 in FIG. 9;

FIG. 18 is an enlarged view of detail 18 in FIG. 9;

FIG. 19 is an enlarged view of detail 19 in FIG. 9;

FIG. 20 is an enlarged view of detail 20 in FIG. 9;

FIG. 21 is an enlarged view of detail 21 in FIG. 10;

FIG. 22 is an enlarged view of detail 22 in FIG. 11;

FIG. 23 is an enlarged view of detail 23 in FIG. 12;

FIG. 24 is an enlarged view of detail 24 in FIG. 12;

FIG. 25 is an enlarged view of detail 25 in FIG. 13;

FIG. 26 is an enlarged view of detail 26 in FIG. 14;

FIG. 27 is an enlarged view of detail 27 in FIG. 15;

FIG. 28 is an enlarged view of detail 28 in FIG. 15;

FIG. 29 is a front, right, top perspective view of the second piece of the sofa, showing my new design;

FIG. 30 is a rear, left, bottom perspective view thereof;

FIG. 31 is a front elevational view thereof;

FIG. 32 is a rear elevational view thereof;

FIG. 33 is a left side view thereof;

(Continued)

FIG. 34 is a right side view thereof;
 FIG. 35 is a top plan view thereof;
 FIG. 36 is a bottom plan view thereof;
 FIG. 37 is an enlarged view of detail 37 in FIG. 29;
 FIG. 38 is an enlarged view of detail 38 in FIG. 30;
 FIG. 39 is an enlarged view of detail 39 in FIG. 31;
 FIG. 40 is an enlarged view of detail 40 in FIG. 33;
 FIG. 41 is an enlarged view of detail 41 in FIG. 35;
 FIG. 42 is an enlarged view of detail 42 in FIG. 35;
 FIG. 43 is a front, right, top perspective view of the third piece of the sofa, showing my new design;
 FIG. 44 is a rear, left, bottom perspective view thereof;
 FIG. 45 is a front elevational view thereof;
 FIG. 46 is a rear elevational view thereof;
 FIG. 47 is a left side view thereof;
 FIG. 48 is a right side view thereof;
 FIG. 49 is a top plan view thereof; and,
 FIG. 50 is a bottom plan view thereof.

The dashed broken lines in the figures are for the purposes of illustrating portions of the sofa and form no part of the claimed design.

The dash-dot-dash broken lines are for notating enlarged views and form no part of the claimed design.

The claim is directed to the collective appearance of the pieces forming the sofa.

1 Claim, 50 Drawing Sheets
